UNITED STATES PATENT OFFICE.

SWEN JOHNSON, OF HURON, SOUTH DAKOTA, AND JOHN JOHNSON, OF HAVRE, MONTANA.

LUBRICATOR.

1,115,676.

Specification of Letters Patent.

Patented Nov. 3, 1914.

Application filed October 25, 1913. Serial No. 797,227.

To all whom it may concern:

Be it known that we, SWEN JOHNSON and JOHN JOHNSON, citizens of the United States, residing, respectively, at Huron, 5 county of Beadle, and State of South Dakota, and Havre, in the county of Hill and State of Montana, have invented certain new and useful Improvements in Lubricators, of which the following is a specification.

10 The present invention relates to improvements in lubricators of the fluid pressure operated type, and in the accompanying drawing the lubricator is illustrated as a direct feed device.

15 The object of the invention is the provision of means for feeding oil or other lubricant under steam pressure, and to improve the construction of the feeding device and provide also an adjusting device for regulating and determining the quantity of lubricant fed through the lubricator.

20 The invention consists in certain novel combinations and arrangement of parts as will be hereinafter more fully described and 25 claimed.

25 In the accompanying drawing is illustrated one complete example of the physical embodiment of the invention constructed according to the best mode so far devised for 30 the practical application of the principles.

35 Figure 1 is a vertical central sectional view of a lubricator involving the novel features of the invention. Fig. 2 is an elevation partly in section of the operating parts of the lubricator.

40 In the preferred embodiment of the invention as illustrated the lubricator comprises the three sections 1, 2 and 3, which are made of suitable metal, preferably brass, and the 45 body section 1 is threaded at 4 to the boss 5 of the coupling 2, while the coupling 2 is connected by threads 6 to the hemispherical cup 3. By this construction and arrangement of the sections 1, 2, and 3, the lubricator may be assembled or dismounted with facility and despatch.

50 The body 1 of the lubricator is adapted to be connected to an oil chamber (not shown) by means of the threaded boss 7, and the oil pipe 8 from the chamber communicates with the horizontal oil passage 9 in the body 1, and this passage 9 communicates with a perpendicular passage 10 in the body 1 and this passage 10 terminates at the end of the nozzle 11 which projects within the glass (not

shown). The lubricator is connected to the glass by means of the coupling nut 12, as usual, and the glass may be drained through the passage 13 in the body of the lubricator which terminates in a pipe 14 of the customary type. 60

The coupling section 2 is bored out to receive the steam pipe 15 which furnishes steam through the passage 16 into the recess 17 of the coupling member, so that steam or 65 fluid pressure may operate to regulate and control the passage of oil through the pipe 8 and passages 9 and 10 to the feed glass.

At the junction of the two passages 9 and 10 in the body 1 a valve seat 18 is provided, 70 and this seat is opened or closed by means of the valve stem 19 which is movable in the central opening 20 of the body section, and a similar opening 21 in the coupling section. A packing nut 22 may be provided 75 in the passage 21 of the coupling member 2 to prevent the escape of steam from the recess 17. This valve stem 19 is formed integral with or is rigidly attached to a disk or piston head 23 which is formed at its 80 under side with a post 24 threaded at 25 and having a reduced end 26 to form a shoulder 27. A diaphragm 28 of suitable flexible material and circular in shape is secured between the head 23 and a clamping 85 nut 29 which is passed up over the post 24 and screwed home over the threads 25 to rigidly hold the diaphragm, and the clamp nut, secure on the post 24, against the disk 23. In Fig. 1 the diaphragm is shown in 90

position secured over the circular edge 30 of the coupling member 2 by means of the flange 31 of the cup 3, and in this position the valve stem 19 is closed against the valve seat 18 by means of a spring 32 which is 95 located between the under side of the nut 29 and a recessed portion at the lower end of the cup 3. The reduced end 26 of the post 24 is projected into a socket portion 34 which is continued from the interior of the 100 cup 3, the lower portion of this socket which is formed by the extension 35 of the cup, is threaded to receive the threads of the turn plug 36.

In the drawings the oil passage is closed 105 and the valve stem 19 is held in closed position by the spring 32. When steam is admitted through the pipe 15 into the chamber or recess 17 above the diaphragm 28, the fluid pressure forces down the piston head 110

23 and diaphragm 28 and with them, the valve stem 19 is pulled downwardly, opening the valve seat 18 for the passage of the oil through the passages 9 and 10, and the oil 5 is thus fed to the part to be lubricated. The spring 32 performs the function of a cushion for the operating parts of the lubricator, and continually urges the valve stem 19 toward its seat 18. The screw plug 32 which 10 is threaded into the boss 35 at the lower end of the cup 3 is provided for the purpose of regulating and adjusting the movement of the valve stem 19 in opening the valve. It will be seen that the upper end of the plug 36 15 will permit only a predetermined downward movement of the valve stem 19 before the plug is struck by the reduced end 26 of the post 24, and when this contact takes place, of course, the valve cannot be opened any 20 wider. By screwing the plug in, or screwing it out, it will be evident that the degree of movement of the valve stem may be varied to adjust the size of the opening of the valve seat.

25 From the above description taken in connection with the drawings it will be evident that the invention provides a device of this

character which will perform the functions of a comparatively perfect lubricator, and will accomplish the purposes set forth as the 30 object of the invention.

Having thus fully described the invention what is claimed herein, is:—

The combination in a lubricator, of a body having a threaded portion, a valve 35 stem and valve seat, a threaded cup member having fluid pressure connection, a diaphragm secured in the cup member, a piston head integral with the valve stem, a post integral with said head, a clamping nut securing the diaphragm to the head, a reduced end on the post, a socket in the cup for said end, and a screw plug threaded into the cup for regulating the movement of the valve stem. 40

45 In testimony whereof we affix our signatures in presence of two witnesses.

SWEN JOHNSON.
JOHN JOHNSON.
